PORTABLE WARNING LAMP

Filed June 14, 1955

INVENTOR.
JULIAN A McDERMOTT

BY *Erin L. Neubauer*
ATTORNEY.

stantially equal to the diameter of a bulb used in connection with a flasher unit. Recess 77 may be lined with a resilient material, such as rubber 76, recess 77 serving as a receptacle for a spare bulb the screw socket 79 of which extends to nearly the edge of the recess 77.

The warning lamp is used in the following manner:

The warning lamp, which is preferably an intermittently flashing lamp, is carried or otherwise transported to its destination. If it is intended to be placed upon the ground, it will stand erect upon the base of battery box 11 in an obvious manner. A spare bulb is entered into the recess provided for that purpose. If it is desired to replace the batteries in the box, the box 11 is opened by the removal of screws 33, so that access to the interior of the box may be had. If a bulb is to be replaced, plate 45 is removed from the rear of reflector box 15 whereby access to the interior of the reflector box may be had.

If it is desired to suspend the lamp on a barricade at an excavation 51, an opening is provided in the barricade into which bracket 32 is placed. A padlock or other retaining device may be entered into the bracket, so that the lamp will remain in adjusted position.

When it is desired to use the warning lamp of the present invention in connection with the tripod illustrated in the drawings, the legs of the tripod are separated and the uprights extended in a conventional manner. Handle 21 of battery box 11 is then entered into slot 75 to suspend the box. The slot 75 is so arranged that box 11 will be suspended directly over one of the legs of the tripod, so that the tripod will attain maximum stability because of the weight of the box 11. Screw 27 may then be turned to permit the disengagement of tube 28 from socket 25. Coil cord 20, one end of which is anchored to the inside of tube 28 permits the extension of the lamp head so that tube 28 may be entered into tube 64 of the tripod.

Inasmuch as the reflector box 15 is made of a non-transparent material, such as metal, it is not normally possible for a person working behind the lamp to determine whether the flasher light is operating properly by 40 a person working behind, such as for instance, a person working in excavation 51. For that reason, space 34 is provided between the sun hood 16 and the reflector box 15. This space makes it possible for a halo of light to be visible from behind the lamp whenever the intermittent flashing of the bulb takes place.

Lamp head 70 in Figure 6 may be held atop the tube 64 in another manner. Instead of sockets 65 and 66, tube 64 may be provided with a pair of oppositely arranged apertures. A flag staff 67 may be placed into 50 each of the said openings, the flag staffs serving as stops for the tube 28 of the lamp head.

The lamp head may be removed from the tripod and placed upon battery box 11 in an obvious and simple manner.

Thus there has been shown and described a simple yet highly effective portable warning lamp in the preferred

forms of its embodiment. Many modifications are apparent and others will become apparent from use. For instance, the several steps described in connection with the use of the device need not be taken in the exact order described; tube 28 may be lengthened considerably, so as to constitute a long upright instead of a short tube and more than one recess for more than one spare bulb may be provided in the battery box.

It is to be understood therefore that the present disclosure is to be regarded as illustrative and descriptive of the best known forms of the invention and not as limitative or restrictive to the exact details shown, applicant reserving the right to make such changes in the construction of his device as may come within the scope of the appended claim without thereby departing either from the spirit or the scope of the appended claim.

Having thus described the invention, what is claimed as new and desired to secure by Letters Patent, is:

A warning lamp of the character described comprising 20 the combination with a tripod; of a battery box, a handle pivotally secured to said battery box, a recess directly over one of the legs of the tripod in which said handle is removably engaged, a cover on said battery box, a single directional lamp including a reflector, a sun hood 25 spaced above and from said reflector whereby stray rays of light are reflected rearwardly when the lamp is in operation, a coil cord having one of its ends secured to said battery box, the other end of said coil cord secured to said reflector, a tubular socket member extending upwardly on said battery box cover, a hollow tube extending normally downwardly from said reflector, said hollow tube entered in said socket member when said reflector is engaged upon said battery box, and said tube disengaged from said socket member and entered in the 30 upright of the tripod when said reflector is positioned on the tripod.
